CONTROL MECHANISM

Samuel G. Green, Alexandria, Va., and Walter H. D'Ardenne, Jenkintown Manor, William J. Meinel, Huntingdon Valley, and Weber de Vore, Horsham Township, Montgomery County, Pa., assignors, by direct and mesne assignments, to Heintz Manufacturing Company, Philadelphia, Pa., a corporation of Pennsylvania

Application December 31, 1943, Serial No. 516,520

4 Claims. (Cl. 89—27)

1

This invention relates to gun control mechanism and more particularly to a novel firing control mechanism for a machine gun mount intended primarily for anti-aircraft use and employable at ease through 360° in traverse and at all angles from a depression -15° to an elevation of $+90^{\circ}$. It is a principal object of the invention to provide such a mount.

In the more modern and now conventional gun mechanisms for anti-aircraft use it has been necessary to employ shoulder braces and back supports for the gunner, for without such accessories the mounts could not be operated with any degree of efficiency. While this comprised an advantage in one sense, the use of such appendages possessed two principal disadvantages. First, of the recoil upon firing this was transmitted directly to the gunner, and secondly, the gunner was thus forced in operation to assume a squatting and somewhat cramped position.

It is another principal object of this invention to obviate these disadvantages and the present mount is so constructed and arranged so that the gunner operates at all times from a standing position which results in greater freedom of action, faster operation and greater accuracy. Moreover, the arrangement makes possible the elimination of shoulder braces and back straps thus greatly reducing the amount of recoil shock transmitted to the gunner.

Still another object of the invention resides in the provision of a novel maneuvering and trigger operating mechanism.

The invention has for an important object the provision of a control mechanism of relatively simple and rugged construction, comprised of light weight components adapted to large scale production and ready assembly.

These and other important objects of the invention will become more apparent from the following description and claims when read in conjunction with the accompanying drawings, in which:

Figure 1 is a side elevation of the preferred form of the invention showing a preferred form of the new control mechanism in place on a gun mount.

Figure 2 is a side elevational view of the cradle assembly.

Figure 3 is a side elevational view of the cradle assembly showing the opposite side.

Figure 4 is a top plan view of the cradle assembly.

Figure 5 is a rear end elevation of the cradle assembly.

2

Figure 6 is a section taken on line 6—6 of Figure 5.

Figure 7 is a section taken on the line 7—7 of Figure 2.

5 Figure 8 is a section taken on the line 8—8 of Figure 3.

Figure 9 is a side elevation of a gun mount showing another embodiment of the invention mounted thereon.

10 Figure 10 is an enlarged detail of the trigger frame illustrated in Figure 9.

Figure 11 is an end detail (partly in section) of the trigger frame shown in Figure 10.

Figure 12 is a section taken on the line 12—12

15 of Figure 10.

A preferred form of the invention is shown in Figures 1 through 8 in which is shown a vertical pedestal support or stand 1 adapted to support detachable legs 2 forming a tripod support. A 20 trunnion bracket 3 is detachably secured to the upper end of the stand 1. The upper portion of the stand 1 is mounted for rotary movement about the vertical axis of the stand so that trunnion bracket 3 is capable of movement in a horizontal 25 plane over 360° .

The upper end of the trunnion bracket 3 supports the cradle assembly 4 for pivoting movement in a vertical plane. The cradle assembly is adapted to carry a gun, such as a cal. .50 Browning water-cooled machine gun 5 (shown in broken lines). The cradle assembly 4 and gun may be elevated from minus 15° to plus 90° .

The cradle assembly 4 further includes a trigger frame, indicated generally by the reference number 6, a trigger side plate mechanism 7 adapted to be secured to the side of the gun 5, a recoil mechanism 8, and a spent ammunition link chute 9. The cradle assembly 4 is adapted to detachably receive an ammunition chest 10 (shown in 40 broken lines).

The trunnion bracket 3, at its base, is provided with means for detachably receiving a shield support 11 carrying an armor plate shield 12 at its upper end.

45 A sighting assembly 13 is adapted to be supported by clamping means 14 to the forward end of the barrel of the gun 5.

The cradle assembly is comprised generally of two parallel spaced side plates 71, 72 bolted 50 in spaced relation by the blocks 73, 74.

The cradle side plate 72 carries an ammunition chest bracket 75 while the cradle side plate 71 supports the ammunition link chute 9.

55 The rear portion of the cradle plate 71 carries the trigger plate assembly 76 connected by a rod

76' to a trigger operating system which is carried by the tubular trigger frame 6 bolted to the side plates 71, 72.

The tubular trigger frame 6 is comprised of two endless tubular members 77, 78, disposed in upright parallel planes (and each of which is bolted to a cradle side plate), and a tubular rear cross support 78'.

Each of the members 77, 78 is provided with a series of brackets 79, 79' respectively, for supporting the operating handle grips 80. The handle grips 80 supported by the brackets 79 carried by the tubular member 77 are supported simply by a bolt and nuts as clearly shown in Fig. 7 which is a cross section through one of the handle grip supports.

The handle grips 80 carried by the brackets 79 rigid with the other tubular member 78 are mounted as shown in Fig. 8 which is a cross section taken on the line 8-8 of Fig. 3. Referring to Fig. 8 it will be noted that these brackets 79' have a transverse opening provided with a sleeve 81. Mounted in each sleeve for rotation therein is a crank 82 adapted to be turned by the handle grip 80. The handle grip 80 is connected to the crank 82 by means of the bolt 83, the inner end of which is threaded in the crank. The reference numeral 84 represents a cone the outer surface of which is serrated so that the handle grip 80 will not turn on the bolt 83.

The arms of the cranks 82 are pivotally connected (as at 85) to a single arc-shaped connecting member 86 which advantageously may be channel-shaped in cross section.

The lowermost crank 82' is provided with two arms (as a bell crank), one of which is pivotally secured to the connecting member 86 and the other of which is pivotally connected to the rod 76'. No handle need be provided for the bracket carrying this crank. A simple spring pressed locking member 86' (Fig. 6) is provided for the purpose of keeping the trigger from firing accidentally.

In operation the handle grips carried by both of the tubular members 77, 78 are grasped by the gunner who can thus move the cradle (and gun) both in elevation or in traverse. Because of this arrangement the gunner may thus direct the gun entirely from a standing position since when the gun is elevated and the tubular trigger frame is depressed, it is only necessary for the gunner to grasp a pair of handle grips disposed higher up on the tubular trigger frame 6.

Through the connecting member 86 any one of the handle grips on the gunner's left will fire the gun when the grip is turned. The action is somewhat similar to that of the handle grip throttle control on a motorcycle. Turning a handle grip will rotate the bell crank 82' thus drawing the rod 76' of the trigger control mechanism 76 which fires the gun.

The forward part of the tubular trigger frame 6 is adapted to carry a small armor plate shield 87 which may be removably bolted thereto as seen for example in Figs. 9, 10 and 11.

Modified form

Figs. 9 through 12 disclose a modified form of the invention having some features in common with the embodiment heretofore described.

With reference to Fig. 9, it will be noted that the amount, like that already described, is provided with a pedestal support 201, legs 202, a

trunnion bracket 203, a cradle assembly 204 and a trigger frame 205 on the rear of the cradle assembly by which the gun 241 can be maneuvered and fired.

In the modified form of the invention, the frame is somewhat similar to that heretofore disclosed, except that it is made of bar stock instead of tubing. Moreover, the trigger handle grips 216 have sprocket wheels 217 on their inner ends, these sprocket wheels being connected by an endless sprocket chain 218. The frame 205 in this instance includes braces 219, 220 each provided with a sprocket wheel 217, 217', respectively, over which the chain also passes. Sprocket wheel 217' is connected with an element 221 provided with a lug 222 adapted to be connected by a rod 223 to the trigger release mechanism of the gun. Fig. 12 is a section through the sprocket 217', member 221 and lug 222.

It will be seen that turning any one of the left-handed trigger handle grips 216 will, through the sprockets and chain, move member 221 with its lug 222 thus actuating rod 223 and firing the gun.

While two preferred embodiments of the invention have been illustrated and described, it is to be understood that changes in structure and arrangement may be made without departing from the inventive concepts which are only to be limited to the extent defined in the following claims.

We claim:

1. In a gun mount, a standard, a cradle assembly supported on said standard for horizontal and vertical pivoting movement, a trigger frame carried by the rear end of said cradle assembly, a series of spaced operating handles carried by said trigger frame and disposed in different horizontal planes, means for actuating the trigger mechanism of a gun carried by said cradle assembly, and means connecting said last named means with said operating handles.

2. In a gun mount to be operated from a standing position and embodying a standard and gun cradle means supported on said standard for horizontal and vertical pivoting movement, a trigger frame assembly secured to said cradle means, said trigger frame comprising a pair of spaced frame members disposed in parallel vertical planes and extending rearwardly and then upwardly and forwardly, a series of spaced handles disposed on each of said frame members and extending laterally therefrom, means for mounting the series of handles on one of said frame members for turning movement, mechanism connecting said mounting means, said mechanism being so constructed and arranged that turning of any one handle will actuate said connecting mechanism, and trigger actuating means associated with said connecting mechanism.

3. In an anti-aircraft gun mount to be operated at all times from a standing position and embodying a standard and gun cradle means supported on said standard for horizontal and vertical pivoting movement, a trigger frame assembly secured to said cradle means, said trigger frame comprising a pair of spaced frame members disposed in parallel vertical planes and extending rearwardly and then upwardly and forwardly, a series of spaced handles disposed on each of said frame members and extending laterally therefrom, means for mounting the series of handles on one of said frame members for turning movement, mechanism connecting said mounting means, said mechanism being so constructed and

arranged that turning of any one handle will actuate said connecting mechanism, and trigger actuating means associated with said connecting mechanism, said connecting mechanism including a connecting element pivoted to each handle mounting means.

4. In an anti-aircraft gun mount to be operated at all times from a standing position and embodying a standard and gun cradle means supported on said standard for horizontal and vertical pivoting movement, a trigger frame assembly secured to said cradle means, said trigger frame comprising a pair of spaced frame members disposed in parallel vertical planes and extending rearwardly and then upwardly and forwardly, a 15

series of spaced handles disposed on each of said frame members and extending laterally therefrom, means for mounting the series of handles on one of said frame members for turning movement, mechanism connecting said mounting means, said mechanism being so constructed and arranged that turning of any one handle will actuate said connecting mechanism, and trigger actuating means associated with said connecting mechanism, said connecting mechanism including a series of sprockets and an endless chain.
